SANDER

Garrett H. Crouse, Baltimore, Md.

Application July 31, 1951, Serial No. 239,523

3 Claims. (Cl. 291—34)

1

This invention relates to a traction sander for automobiles and has for its principal object the provision of a sanding device in which the flow of sand is controlled by slides so arranged that the device will always be ready for service.

A further object of the invention is to provide means for blowing fresh air into a sand reservoir close to the port or ports of exit.

A still further object of the invention is to provide a sanding system for automobiles in which the sand hoppers or reservoirs are so shaped as to provide for excellent discharge of the sand and yet to be mounted in the trunk of an automobile without encroaching too greatly on the storage space.

In the drawings:

Figure 1 is a rear elevation of the device as mounted in the trunk of an automobile;

Figure 2 is a detail of a slide operating magnet;

Figure 3 shows the dash control.

Traction sanders have been used for a great many years in connection with locomotives and many attempts have been made to modify these for use with automobiles. Tests of previously known sanders indicate that where the motor exhaust is used for sand discharge there is entirely too much condensation from the pipes and this dampens the sand in the sand tanks and clogs the valves. This difficulty is eliminated in the present device by having a relatively small motor-driven blower which discharges fresh air under pressure near the point of discharge of the sand from the sand hopper. A further objection to previous devices which use slides for controlling the volume of sand discharged and move the slides between leather facings the slides become corroded possibly due to an acid content of the leather. By substituting felt for leather all difficulty with sticking valves has been eliminated.

Referring to Fig. 1, there are two hoppers 10 and 11 the tops of which extend from side to side of the trunk compartment of an automobile, located as high as possible but leaving space so that the openings 12 can be used to fill the hoppers with sand. These openings 12 are closed in any desired manner as, for example, by a lid 14 or a sliding closure such as 15. I prefer that both sides of each hopper shall slope, the outside wall 16 sloping materially less than the inner wall 17. While the sizes may vary within wide limits depending upon the type of automobile, I find a very convenient size to be 11" high over all, about 7" thick front and back with an over-all width at the top of the two hoppers of

2

about 44". The device illustrated in Fig. 1 is quite a bit deeper relatively and these hoppers need only be 4" from front to back. In any event the two hoppers should provide between them a space bounded by the wall of the trunk and the two sloping walls 17 of the twin hoppers to provide a compartment which will accommodate the motor, the blower and other accessories with minimum diminution of the storage space in the trunk.

The two hoppers each have a base 22 above the flaring skirt 9, such base having a pair of openings 23 and 24 leading to divergent nipples 25 and 26 threaded as at 27 for connection to tubes, one leading to a point just in front of the contact with the ground of a rear tire while a similar tube joined to the other nipple would lead to a point just behind the same rear wheel. The slides are numbered 31 and 32 each having a beveled end 33 which can be moved to engage the felt coating 34 surrounding a central bar or bridge 35 forming the boundary between the openings or ports 23 and 24. On both sides of the slides 31 and 32, above and below, are layers 18 of felt. This material is ideal for the purpose and avoids all sticking of the steel slides. The thickness of the felt should be about as great as the thickness of the slide, a minimum of a quarter of an inch being preferred.

Practice indicates that the sand may not discharge from the hoppers thru the openings 23 or 24 in a perfectly satisfactory manner unless there is a discharge of air just above the bridge 35. I therefore mount in each of the hoppers 10 and 11 an air discharge pipe 37, having a down-turned end 38 which ends in a flaring nozzle 39. The nozzle could be spaced over the opening 23 or the opening 24 but I find the best results are achieved when the nozzle is directly over the bridge 25 and the angle of the flare is such as to form a cone which would intersect the plane of the base 22 within the openings 23 and 24 so that the full effect of the blast of air would be had over the two openings at a point just above the slides. Each of the pipes 37 lead from the compartment 40 which is a pressure air reservoir fed by a blower 41 preferably directly connected to the blower motor 42.

In case the equipment should be factory installed the major portion of the sand hoppers could be located inside the automobile body (steel top only) with filler closures on the outside near the rain deflector gutter but the slides and blower would be in the trunk space. It is my intention that the blower motor be operated

independently of the slides and that it be started at the first indication of slick conditions. A light on the dash will be lit when this motor is operating and this will serve as a pilot to locate the adjacent switch governing the slides discharging in front of the rear wheels.

While there are many specific arrangements by which the valve slides 31 and 32 could be moved, I have illustrated in Figure 2 a convenient form. In the embodiment there shown, which is illustrative only, valve slide 32, which is a flat piece of metal or plastic, carries a stem 45 which is the armature of a solenoid 46. When the coil 47 of the solenoid is energized the rod 45 and the slide 32 are pulled to open position, as illustrated in Figs. 1 and 2, against the urge of spring 48 which normally holds the slide in closed position with its downwardly beveled point 33 in light contact with the heavy felt covering 34 of the bridge 35. As previously stated, the electrical connections are illustrative only. In my last model I used circular magnets which are excellent and take up very little space. They are also readily adjustable taking the place of the stop-washer 49 which is threaded on the stem or armature 45 for adjusting the amount of opening of the slides when their coils are energized.

In Figure 3 is shown the addition to the dash. The support 50 is a rolled angle bracket carrying three simple pull switches 51, 52 and 53 connected respectively to the blower motor, the slides 31, and the slides 32. I much prefer signal lights above each switch to show that that element is energized, for example, a yellow light 55 over the blower switch 51, a green light 56 over the forward discharge slide switch 52 and a red light 57 over the rear-of-the-wheel discharge slide switch 53.

While I can readily have a single rotary switch on the dash with five positions: off; blower motor only; blower plus slides 31; blower plus slides 32; and blower plus slides 31 and slides 32, there is always danger that in an emergency an excited driver might turn this switch to the wrong position so my preference, based on extended use, is to have the three pull switches as shown in Fig. 3 as in this way the driver first pulls the first switch as soon as it seems an emergency might develop. The excess current is slight as the blower only gives a pressure of about two inches of water. The light 55 is readily seen and when sand is required the driver (leaving switch 51 pulled out) pulls the middle switch and does not apply his brakes until he sees by the green light

that sand is flowing. This makes the device almost fool-proof. The air keeps the sand in motion and ready to start the instant the slide is opened.

5 What I claim is:

1. A sanding device for automobiles including a sand reservoir having a base in which there is an opening, a bar crossing the opening to form two passageways for discharge of the sand, a closure for each of the two passageways, means for opening and closing the closures, and air discharging means including a pipe having a single nozzle discharging a stream of air downward on the bar and into both of the two passageways.

10 2. The device of claim 1 in which the pipe has a flared nozzle, and means are provided for controlling the operation of the air discharging means independently of the movement or position of the closures, whereby the air may be discharged prior to the opening of either of the closures.

15 3. The device of claim 1 in which the closures are reciprocating plates moving toward and away from the bar, the closure operating means include electro-magnets positioned away from the margins of the reservoir base, and means are provided for adjustment at will of the amount of the travel of the plates, whereby to control the amount of said which may pass thru either of the two passageways.
